H. M. SHEER

BURNER WELL

Filed Jan. 26, 1924

Inventor

Henry M. Sheer

By Vernon G. Hodges
his attorney

UNITED STATES PATENT OFFICE.

HENRY M. SHEER, OF QUINCY, ILLINOIS.

BURNER WELL.

Application filed January 26, 1924. Serial No. 688,805.

My invention relates to an improvement in burner wells.

This invention includes a drain pipe with the burner well, the idea of the drain being 5 to prevent the burner well from becoming flooded. The drain outlet is intended to be much larger than the oil inlet and will take care of several times the amount of oil that can possibly enter the inlet. When the oil is 10 fed to the burner in excess of requirements as for instance in the initial feed, the surplus will escape through the drain. The burner will naturally consume some of this excess oil while it is passing through the 15 drain, but never enough to cause the flame to smoke.

Therefore, my object in using the drain pipe is to place a catch basin entirely beyond the heat of the burner. This present 20 invention provides a burner that can not be flooded and can not be made to smoke and soot.

A further object of the complete drain is not merely to prevent the oil well from flooding 25 and overflowing but to eliminate the possibility of the flame smoking. A mere overflow does not eliminate smoking, neither does it eliminate danger since it maintains a given depth of oil in the bottom of the burner 30 well, and when the oil becomes hot enough to vaporize which will happen sooner or later, and which may happen any time, the vapor will smoke and the incoming oil will flow over the top of the oil well. It is my 35 aim to develop an oil heater to a point where it is fundamentally safe so that all so-called fire-proof devices will seldom if ever be really needed.

In the accompanying drawings:

40 Figure 1 is a sectional view; and
Fig. 2 is a plan view.

The numeral 1 represents the burner well. 45 2 is the supply pipe and 3 and 4 are the usual perforated screens. The burner well has a wide flat bottom over which the oil is spread and vaporized.

The numeral 5 is a drain leading from the bottom of the burner well. The drain outlet 6 is larger than the oil inlet 7, making it

impossible to flood or overflow the burner 50 well.

The pipe 5 leads to a stuffing-box 8 located below the burner well. A second drain pipe 9 having a goose-neck 10 therein leads from the stuffing-box 8 to the catch basin 11. 55 When the goose-neck is turned as shown by full lines in Fig. 1 it temporarily closes the drain while the burner is being primed. When the goose-neck is turned as shown by dotted lines in Fig. 1, it allows the excess oil 60 to flow to the catch basin 11 and provides a seal or trap to prevent the air from passing through the drain pipe to the burner well.

The drain is preferably located on the opposite side of the burner from the oil inlet, 65 instead of an overflow which is commonly in use. This invention differs from that and has a drain from the bottom of a wide flat bottomed burner well. A complete drain of this description not only prevents the burner 70 well from flooding and overflowing but it completely eliminates the possibility of the flame from smoking, but a mere overflow does not eliminate smoking nor does it prevent danger because it necessarily maintains 75 a given depth of oil in the bottom of the burner well. In other words, an overflow is at some point above the bottom. This drain is at the lowest possible point in the flat bottom of the burner well. 80

In normal operation the goose-neck 10 will be in the dotted line position of Fig. 1 so that the drain will remain wide-open to carry off any excess oil from the burner well but at the same time the drain pipe will always have a seal or trap to prevent air from entering the burner through the drain pipe and thereby effecting a flame. When it is desired to prime the burner, the goose-neck 90 10 is turned up into the full line position 90 of Fig. 1 thereby stopping the flow of oil therethrough. After the burner is once generated, no oil whatsoever will reach the drain outlet in the burner well, as the oil necessary 95 to produce a maximum flame will be vaporized long before it reaches the drain outlet at the point opposite the oil inlet. But when oil is fed to the burner, as for instance in the

initial priming, in excess of requirements, the drain is there to take care of the surplus which immediately escapes through it.

I claim:

- 5 A burner well having supply and drain pipes connected therewith, a goose-neck extending laterally from the drain pipe and capable of being turned relative thereto

whereby the position of the goose-neck may be reversed, the outer bent portion of the 10 goose-neck when turned in its uppermost position being above the bottom of the burner well.

In testimony whereof I affix my signature.

HENRY M. SHEER.
